Harry R. Tovea Inventor

By Geo. F. Kimmel
Attorney

UNITED STATES PATENT OFFICE.

HARRY R. TOVREA, OF PORTLAND, OREGON.

MILKING-STOOL.

1,295,238.

Specification of Letters Patent. Patented Feb. 25, 1919.

Application filed June 9, 1917. Serial No. 173,802.

To all whom it may concern:

Be it known that I, HARRY R. TOVREA, a citizen of the United States, and resident of Portland, in the county of Multnomah and State of Oregon, have invented certain new and useful Improvements in Milking-Stools, of which the following is a specification.

This invention relates to new and useful improvements in milking stools, and the primary object of the invention is to provide a device of this character which is especially applicable for use by dairymen, farmers, etc., and which is provided with a seat, and a pail support that is associated therewith, and which is adapted to hold the pail stationary in position during the milking operation. Furthermore, due to the peculiar formation of the frame, which, as will be borne in mind is provided with converging arms 7 and 8, thus rendering the same substantially V-shaped, the stool will be rendered readily portable and further, the arranging of the reduced forward portion thereof in proper position to facilitate the milking operation will be facilitated. Also, since the width of the forward portion of the frame is materially less than the rear portion thereof, it will be also understood that the liability of the overturning of the same due to the kicking of the animal will be lessened, since, the frame will occupy the least possible space at its forward end. However, by reason of the widened rear portion of the stool, it will be also understood that the user will be provided with a stable form of seat and support and further, a support which will not be apt to be overturned by reason of the shifting of the weight of the person on the seat to one side thereof.

Since the seat 3 is supported on the inverted U-shaped standard 4 which, in turn is directly connected to the opposite sides of the rear portion of the frame, attention is directed to the fact that the stress will be equally and directly applied to the frame sides and in consequence, will serve to stabilize the same against overturning or other undue movement.

Another object of the invention is to provide a device of this character which is movable, so that the same may be quickly moved into position when the animal moves, without the necessity of the operator changing his position.

A still further object of the invention is to provide a device of this character which

is absolutely sanitary, easily and simply constructed, inexpensive to manufacture, and one which will be very efficient in operation.

With these and numerous other objects in view my invention consists of the novel features of construction, combination and arrangement of parts which will be herein-referred to and more particularly pointed out in the specification and claim.

In the accompanying drawings:

Figure 1 is a top plan view of the device, and

Fig. 2 is a side elevation of the same.

In describing my invention I shall refer to the drawings in which similar reference characters designate corresponding parts throughout the several views. The numeral 1 designates the seat supporting frame, which is substantially rectangular in shape, and which is normally disposed in an upright position, as clearly shown in Fig. 2 of the drawings, and secured to the lower edge of said frame are a pair of supporting wheels 2 which are connected thereto.

A seat 3 is adjustably connected with the frame by means of a substantially U-shaped support 4, which has its connected edge secured to the bottom of the seat, while the sides of the support extend downwardly, and are disposed adjacent the inner side, of the sides of the frame 1. These sides of the connecting means are provided with a plurality of vertically spaced apertures 5 therein, and the adjacent sides of the frame 1 are each provided with an aperture, through which a locking pin 6 is adapted to project, so as to hold the seat 3 in various vertically adjusted positions.

Projecting laterally and downwardly from the opposite sides of the frame 1 are a pair of converging arms 7 and 8, which have journaled between the forward extremities of the same a supplemental wheel 9, that is disposed substantially in a single horizontal plane with the wheels 2 of the frame 1. These arms 7 and 8 are formed preferably of metal strips, that have their ends that are connected with the frame 1 secured thereto by bolts 10 that project through said sides of the frame. This connection is clearly shown in Figs. 1 and 2 of the drawings.

Connected with the converging arms 7 and 8, intermediate the ends of the same, is an inverted substantially U-shaped frame 11, having its opposite sides provided with

a plurality of spaced apertures 12 therein, and the said sides of the frame are connected with the arms by locking pins 13 that are adapted to project through any of said apertures, and through an alining aperture that is formed in each of the arms 7 and 8. These pins are preferably formed of a bolt with a nut on one end thereof, so that the same are easily detachable, for quickly vertically adjusting said frame. Secured to the top of the frame 11, are a pair of cross strips 14 and 15, which are connected with the frame at their point of intersection, and the strips have their extremities provided with longitudinally extending slots 16 therein. Secured to said extremities of the strips are angular holding members 17, that have bolts 18 secured to their horizontal portions, that are adapted to project downwardly through the slots 16 and said bolts are held in position by locking nuts 19 on the lower end thereof as clearly shown in Fig. 2 of the drawings. These cross strips are adapted to form pail holding means, and the adjustable angular members 17, allow the same to be so adjusted as to receive different sized pails. The pail holding means is disposed in a horizontal plane beneath the horizontal plane of the seat, so as to hold the pail in operative position when the device is in use. In operation, the pail is positioned on the pail holding support, the same having been adjusted to correspond to the size of the bottom of said pail, and the device is positioned beneath a cow, so that the pail will be held or supported directly beneath the udder of the animal. The operator then takes his position on the seat 3, and as the pail supporting means is disposed in a plane beneath that of the seat, the pail will be held in correct position for milking. The pail holding means, and the seat are vertically adjustable as has been hereinbefore described, so that the device may be adjusted accordingly as desired. Attention is particularly directed to the fact that the supporting means of this device, which includes

the main frame 1 and the diverging arms, are provided with wheels, whereby the stool is adapted to move easily, to correspond with the movement of the animal, without the operator changing his position. 50

From the foregoing description, taken in connection with the accompanying drawings, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claim 60 appended hereto. 65

As clearly shown in Fig. 1 of the drawings the bolt supporting means is horizontally adjustable toward and from the seat 3. The outer sides of the arms 7 and 8 are provided with vertical guide lugs 20 to prevent the portion 11 from tilting. 70

Having fully described my invention, what I claim as new, and desire to secure by Letters Patent, is:

A device of the character described comprising a substantially V-shaped frame, wheels secured to the reduced forward extremity of the frame and the widened rear extremity thereof, the wheels secured to said rear extremity being capable of turning with relation to the frame whereby to facilitate guiding thereof during movement, an inverted substantially U-shaped standard secured to the opposite sides of the rear extremity of the V-shaped frame and capable of being adjusted vertically with relation thereto, a seat carried by said U-shaped standard, and adjustable bucket supporting means engaged with the intermediate portion of the frame forwardly of said seat. 80 85 90

In testimony whereof, I affix my signature hereto.

HARRY R. TOVREA.
